UNITED STATES PATENT OFFICE.

ROBERT A. ELLISON, OF CINCINNATI, OHIO.

GAME.

Application filed April 22, 1921. Serial No. 463,592.

To all whom it may concern:

Be it known that I, ROBERT A. ELLISON, a citizen of the United States of America, and a resident of Cincinnati, in the county 5 of Hamilton and State of Ohio, have invented a new and useful Improvement in a Game, of which the following is a specification.

My invention relates to games of the type 10 wherein dummy figures are made to climb a pole or to move over a course and in which the movement of the dummy over the course is conditioned by the action of a player who manually operates a rotatory wheel, or similar device, connected with the dummy moving mechanism.

The game is electrically operated and as disclosed herein, comprises a series of masts B, up which a dummy figure is drawn by a 20 cable a¹⁷ which is wound upon a reel a' revolvably mounted on a continuously moving shaft A. A drum a⁴ is mounted upon the continuously moving shaft and is adapted to transmit motion from the shaft to the 25 reel under certain conditions.

These conditions are created by and subject to the action of a player in manipulating a hand wheel d'.

An object of my invention is to provide 30 a game of the type referred to in which a player must continuously actuate his hand wheel in order to move the dummy along the course, and in which failure to actuate the hand wheel at a speed intermediate a 35 minimum and a maximum speed, will cause the player to lose control of the dummy.

Another object is to provide a game of the kind referred to wherein the complicated mechanisms heretofore employed, may 40 be dispensed with.

Another object of my invention is to provide a game of the kind referred to that is simple in construction and operation.

These and other objects are attained by 45 the means described herein and disclosed in the accompanying drawing, in which—

Fig. 1 is a diagrammatic view of a mechanism embodying my invention.

Fig. 2 is an enlarged sectional view on 50 line 2—2 of Fig. 1.

Fig. 3 is a perspective view of a series of devices such as is shown in Fig. 1, parts being broken away, and showing, diagrammatically, the wiring of the devices.

55 The shaft A is continuously revolved from any suitable source of power such as

a motor not shown. If desired, the shaft A may be actuated by means of a pulley a mounted thereon, driven from any suitable source. A reel a' is revolvably mounted upon the shaft A and has a lug a² mounted upon one of the sides a³ thereof. A drum a⁴ is fixedly mounted on the shaft A adjacent the reel a' and has the contact rings a⁵ and a⁶ mounted upon it. Suitable 60 collars are used to space the reel and drum. Interiorly of the drum is mounted an electro-magnet a⁷ having the opposite end of its winding connected to the rings a⁵ and a⁶. An armature a⁸ adapted to be actuated by the electro-magnet is pivotally mounted intermediate its ends interiorly of the drum, and is adapted to be moved about its pivotal 70 mounting a⁹ and to engage at one end upon the core of the electro-magnet when the electro-magnet is energized. A spring a¹⁰ yieldingly spaces the armature from the electro-magnet core. An arm a¹¹ is formed on the other end of the armature. A reciprocating pin a¹² is mounted upon the end 80 of the drum and is adapted to assume a position wholly within the drum or partly beyond the drum. A spring a¹³ yieldingly retains the pin in its normal position wherein part of the pin extends beyond or out 85 of the drum. Normally the arm a¹¹ formed upon the armature a⁸ assumes a position immediately adjacent the innermost end of the pin and precludes the moving of the pin from its normal position to a position wholly 90 within the drum. The pin is disposed at such a place upon the end of the drum that when the drum is revolved, the pin may engage the lug a² on the reel a'. The outer or forward end of the pin has formed upon 95 it the converging faces a¹⁴ and a¹⁵ adapted to engage the lug a². The faces a¹⁴ and a¹⁵ are made converging so that the lug a² will cause the pin to move into the drum against the yielding resistance of the spring a¹³ at 100 any time when the arm a¹¹ is moved from its normal position. When the arm a¹¹ is in its normal position, the pin is unable to enter the drum, wherefor the pin and the lug a² are retained in driving relation and the reel a' is revolved upon the shaft A. Contacts are made upon the rings a⁵ and a⁶ by suitable brushes a¹⁶ and a¹⁷. A cable a¹⁸ has one of its ends secured upon the reel a' and extends through the hollow 110 mast B mounted vertically above the reel a'. The cable a¹⁸ extends about a pulley

b mounted in the upper end of the mast *B*, and has its other end secured upon a sleeve *b'* slidably mounted upon the mast *B*. The mast has a longitudinal slot *b*² through 5 which the pin *b*³ extends. The pin has secured upon its inner end the one end of cable *a*¹⁷ and extends through the sleeve *b'*. A dummy may be mounted on the outer end of the pin *b*³.

10 A revoluble shaft *D* is mounted upon a suitable counter or stand *d* and has mounted upon one end of it a hand wheel *d'* whereby the shaft *D* may be revolably actuated. The contact rings *d*² and *d*³ are mounted upon the 15 shaft *D* below the stand *d*, and are engaged by suitable brushes *d*⁴ and *d*⁵ respectively. A radial arm *d*⁶ is mounted upon the lower end of the shaft *D*, and has pivotally mounted upon it, adjacent its outer end, a pendulum *d*⁷. The pendulum normally assumes a vertical position as shown at *d*⁸ in dotted lines. Electrical contacts *d*⁹ and *d*¹⁰ are mounted upon the arm *d*⁶ and are adapted to be engaged by the pendulum *d*⁷. The pendulum is adapted to make an electrical connection with either of the contacts *d*⁹ and *d*¹⁰. Normally the pendulum engages contact *d*¹⁰. The pendulum is electrically connected with the contact ring *d*², and the contacts *d*⁹ and 25 *d*¹⁰ are electrically connected with the contact ring *d*³. The contact brush *d*⁴ is connected with the positive pole of the battery *C*. The brush *d*⁵ is connected with the brush *a*¹⁵, and the brush *a*¹⁶ is connected with the 30 negative pole of the battery *C*.

An electrically controlled lock *E* comprises a casing *e* within which is disposed an electro-magnet *e'* adapted to move the armature *e*² pivotally mounted intermediate its 40 ends within the casing. The armature *e*² has a catch *e*³ formed on the end thereof spaced from the electro-magnet adapted to normally engage a notched lug *e*⁴ formed on the switch arm *e*⁵ pivotally mounted on the 45 casing *e*. One end of the switch arm is electrically connected with the positive pole of the battery *C*. An electrical contact *e*⁶ is connected with the brush *a*¹⁵, and is adapted to be engaged by the switch arm *e*⁵ when 50 released from the catch *e*³.

A bracket *F* is mounted above the mast *B* and has mounted upon it an electro-magnet *f* having one end of its winding electrically connected with a conductor rod *f'* connected with the positive pole of battery *C'*. The electro-magnet *e'* contained within the casing *e* has one end of its winding electrically connected with the rod *f'* and has the other end of its winding electrically connected with a conductor rod *f*². A lever arm *f*⁴ is pivotally mounted intermediate its 55 ends upon the bracket *F* and the opposite ends thereof are adapted to engage the contact bar *f*⁵ and the core of the electro-magnet *f*. The arm *f*⁴ is made of suitable ma-

terial so that it will serve as an armature that will be retained upon the core of the magnet *f* when this magnet is energized, and that it may be employed to close an electrical circuit embracing itself and the contact bar *f*⁵. 70 A rod *f*⁶ is pivotally mounted upon the lever arm *f*⁴ intermediate the pivotal connection of the lever arm upon the bracket *F* and that end of the lever arm adapted to engage the core of the electro-magnet *f*. An electric light bulb *f*⁷ is mounted adjacent the top of the mast *B* and is electrically connected with the conductor rod *f'*. The conductor rod *f*² is connected with the wires leading from the electro-magnet *f* and the light bulb *f*⁷, and 75 makes an electrical contact with the lever arm *f*⁴ whereby a current may pass through the lamp *f*⁷ and the electro-magnets *f* and *e'* when the lever arm *f*⁴ engages the contact bar *f*⁵. The contact bar *f*⁵ is electrically connected with a conductor rod *f*³ connected with the negative pole of the battery *C'*. 80

A switch *G* is interposed in the circuit intermediate the conductor rod *f*³ and the negative pole of the battery *C'*. 85

The circuits embracing the batteries *C* and *C'* may be wired in parallel off of a common battery if desired.

The operation of my game is as follows:

Normally the circuit embracing the battery *C'* is open and the circuit embracing the battery *C* is closed, the current from battery *C* passing from the positive pole thereof to the brush *d*⁴, the pendulum *d*⁷, contact *d*¹⁰, brush *d*⁵, brush *a*¹⁵, electro-magnet *a*⁷, brush *a*¹⁶ 90 and back to the battery, thereby retaining the armature *a*⁸ in an abnormal position. Normally the switch arm *e*⁵ is held out of engagement with the electrical contact *e*⁶ by the lock *E*. The shaft *A* is normally being 95 rotatively actuated. The drum *a*⁴ revolves with the shaft *A* and as the latch *a*¹¹ engages the lug *a*² mounted in the reel *a'*, the lug is moved against the spring *a*¹² whereby the drum revolves without actuating the reel. The current passing through the electro-magnet *a*⁷ retains the armature *a*⁸ in such 100 position that the arm *a*¹⁰ thereon will not engage the pin *a*¹¹. When a player actuates the hand wheel *d'*, the centrifugal force directed upon the pendulum *d*⁷, which pendulum normally engages contact *d*¹⁰, causes the lower end of the pendulum to spring outwardly and assume the position shown in full lines at *d*⁷ in Fig. 1. The circuit passing through the electro-magnet *a*⁷ is therefore broken and the spring *a*⁹ moves the armature *a*⁸ to its normal position wherefore the arm *a*¹⁰ of the armature lies immediately adjacent the rear or inner end of the latch *a*¹¹ 105 and precludes the movement of the pin into the drum when the pin engages the lug *a*². When the pin then engages the lug *a*², the pin carries the lug with it, wherefore the reel *a'* is rotatively actuated and the 110

120

125

130

cable a^7 is wound upon the reel, thereby causing the sleeve b' to be elevated upon the mast B. Should the player move the hand wheel d' either too fast or too slow, wherefore the pendulum engages either of the contacts d^9 and d^{10} , the circuit through the magnet a^7 is closed and the player loses control of the sleeve b' and does not again gain control of the sleeve until the speed of the hand wheel is brought within certain limits. When a player has succeeded in elevating the sleeve b' to its uppermost limit, the sleeve engages the rod f^6 and moves the rod about its pivotal mounting upon the bracket F, thereby closing the circuit in which the electro-magnets e' and f , and the lamp f^7 are embraced. The lamp f^7 and the electro-magnets e' and f are wired in parallel. The closing of the circuit embracing the battery C' causes the electro-magnet e' to be energized, wherefore the switch arm e^5 is released from the catch e^2 formed on the armature e^4 , gravity causing the switch arm to move about its pivotal mounting wherefore the switch arm engages the contact e^6 , thereby closing the circuit embracing the battery C wherefore the sleeve b' will fall to the bottom of the mast B. Simultaneously with the energizing of the electro-magnet e' , the bulb f^7 is illuminated and the electro-magnet f is energized. The lamp f^7 functions as an annunciator of the winner, and the electro-magnet f retains the arm f^4 in engagement with the contact bar f^5 . When the game is again to be placed in its normal position, the switch G is opened, whereupon the magnet f is de-energized and the rod f^6 falls and assumes its normal position. The switch G is then closed and the switch arm e^5 is disengaged from the contact e^6 and is secured by the catch upon the armature e^2 . If desired the switch arm e^5 may be spring actuated, as shown in dotted lines, instead of being gravity actuated. The switch G is preferably retained in a normally closed position by means of a spring g .

When a plurality of these devices are mounted adjacent one another, a game is provided in which each player tries to win a race of the dummies to the top of the mast by having the sleeve controlled by his hand wheel to first reach the top of the mast. The switch arm d^5 is wired so as to be common to all of the mechanisms mounted at the bottom of the masts, and the lock E is wired so as to be common to all the mechanisms at the tops of the masts, so that when any one sleeve b' reaches its uppermost limit, the closing of the circuits by the switch arm e^5 and a lever arm f^4 serves to release all of the reels a' from the drums, and the lamp above the mast of the winner will continue to burn until the person in charge opens the switch G.

It is obvious that the mechanisms mounted within the drum and upon the shaft D may

be operated in either a normally open or closed circuit.

What I claim is:

1. In a device of the class described the combination of a revolute shaft, a course 70 over which a dummy may be moved, a dummy, electrically responsive means adapted to be actuated by the shaft and to displace the dummy over the course, manually operative means controlling the electrically responsive means, and a source of electrical energy for the electrically responsive means.

2. In a device of the class described the combination of a revolute shaft, a course 80 over which a dummy may be moved, a dummy, electrically responsive means adapted to be actuated by the shaft and to displace the dummy over the course, manually operative means controlling the electrically responsive means, a source of electrical energy for the electrically responsive means, and an annunciator adapted to be actuated when the dummy has been moved over the course.

3. In a device of the class described the 90 combination of a revolute shaft, a course over which a dummy may be moved, a dummy, electrically responsive means adapted to be actuated by the shaft and to displace the dummy over the course, manually operative means controlling the electrically responsive means, a source of electrical energy for the electrical responsive means, and means adapted to render the electrically responsive means inoperative upon the movement of the dummy over the course.

4. In a device of the class described the combination of a revolute shaft, a course over which a dummy may be moved, a dummy, electrically responsive means adapted to be actuated by the shaft and to displace the dummy over the course, manually operative means controlling the electrically responsive means, a source of electrical energy for the electrically responsive means, an annunciator adapted to be actuated when the dummy has been moved over the course, and means adapted to render the electrically responsive means inoperative upon the movement of the dummy over the course upon the operation of the annunciator.

5. In a device of the class described the combination of a revolute shaft, a course over which a dummy may be moved, a dummy, a reel mounted loosely upon the shaft, a connector between the reel and the dummy whereby movement of the reel serves to displace the dummy over the course, electrically responsive means adapted to be conditioned whereby rotatory motion from the 125 shaft may be transmitted to the reel, manually operative means adapted to control the conditioning of the electrically responsive means, and a source of electrical energy for the electrically responsive means.

6. In a device of the class described, the combination of a revolute shaft, a plurality of courses over each of which a dummy may be moved, dummies, individual means for displacing each dummy over its respective course each of said individual means being adapted to be actuated by the shaft, and manually operative means controlling the transmission of motion from the shaft 10 to the displacing means.

7. In a device of the class described, the combination of a revolute shaft, a plurality of courses over each of which a dummy may be moved, dummies, individual means for displacing each dummy over its respective course, each of said individual means being mounted on the shaft and adapted to be actuated by the shaft, and manually operative means controlling the transmission 20 of motion from the shaft to the displacing means.

8. In a device of the class described, the combination of a revolute shaft, a plurality of courses over each of which a dummy may be moved, dummies, individual means for displacing each dummy over its respective course each of said individual means being adapted to be actuated by the shaft, manually operative means controlling the 30 transmission of motion from the shaft to the displacing means, and an annunciator adapted to be actuated when any dummy has been moved over its entire course.

9. In a device of the class described, the combination of a revolute shaft, a plurality of courses over each of which a dummy may be moved, dummies, individual means for displacing each dummy over its respective course each of said individual means being adapted to be actuated by the shaft, manually operative means controlling the 40 transmission of motion from the shaft to the displacing means, and an annunciator for each course adapted to be energized when 45 its corresponding dummy has been moved over its respective course.

10. In a device of the class described, the combination of a revolute shaft, a plurality of courses over each of which a dummy may be moved, dummies, individual means for displacing each dummy over its respective course each of said individual means being adapted to be actuated by the shaft, manually operative means controlling the 50 transmission of motion from the shaft to the displacing means, an annunciator for each course adapted to be energized when its corresponding dummy has been moved over its respective course, and means to release all the displacing means on the energizing of any one annunciator.

11. In a device of the class described, the combination of a revolute shaft, a plurality of courses over each of which a dummy may 60 be moved, dummies, means for displacing

each dummy over its respective course each adapted to be actuated by the shaft, manually operative means controlling the transmission of motion from the shaft to the displacing means, and means to release all the 70 displacing means from the action of the shaft on the movement of any dummy over its entire course.

12. In a device of the class described, the combination of a revolute shaft, a plurality 75 of courses over each of which a dummy may be moved, dummies, means for displacing each dummy over its respective course each adapted to be actuated by the shaft, manually operative means controlling the transmission of motion from the shaft to the displacing means, an annunciator adapted to be actuated when any dummy has been moved over its entire course, and means to retain the annunciator in an operative position 80 until the annunciator is manually rendered inoperative.

13. In a device of the class described, the combination of a revolute shaft, a plurality 85 of courses over each of which a dummy may be moved, dummies, means for displacing each dummy over its respective course each adapted to be actuated by the shaft, manually operative means controlling the transmission of motion from the shaft to the displacing means, an annunciator adapted to be actuated when any dummy has been moved over its entire course, means to retain the annunciator in an operative position 90 until the annunciator is manually rendered inoperative, and manually operative means to render the annunciator inoperative.

14. In a device of the class described the combination of a revolute shaft, a plurality 100 of courses over each of which a dummy may be moved, dummies, means for displacing the dummies individually over the course and each comprising a drum mounted on the shaft and adapted to revolve therewith, a reel revolubly mounted on the shaft, a connection between the dummy and the reel whereby rotatory motion of the reel serves to move the dummy over the course, and means on the drum adapted to transmit motion from the drum to the reel, and manually operative means controlling the transmission of motion from the means mounted on the drum to the reel.

15. In a device of the class described, the combination of a revolute shaft, a plurality 115 of courses over each of which a dummy may be moved, dummies, means for displacing each dummy over its respective course each adapted to be actuated by the shaft, manually operative means controlling the transmission of motion from the shaft to the displacing means, an annunciator for each course adapted to be energized when its corresponding dummy has been moved over its respective course, and means to retain the 120 125 130

actuated annunciator in operative condition until manually rendered inoperative.

16. In a device of the class described, the combination of a revolute shaft, a plurality of courses over each of which a dummy may be moved, dummies, means for displacing each dummy over its respective course each adapted to be actuated by the shaft, manually operative means controlling the transmission of motion from the shaft to the displacing means, an annunciator for each course adapted to be energized when its corresponding dummy has been moved over its respective course, means to retain the actuated annunciator in operative condition until manually rendered inoperative, and means to release all the displacing means on the energizing of any annunciator.

17. The combination with a source of electrical supply, provided with a supply circuit, a course over which a dummy may be moved, a dummy, a revolute shaft, electrically controlled means adapted to be actuated by the shaft and to move the dummy over the course, electrically communicating with said supply circuit, a plurality of contacts adapted to be brought in circuit with said electrically controlled means to govern the movement of the dummy actuating means by the shaft, and manually operable means controlling the bringing of the various contacts into the supply circuit.

18. The combination with a source of electrical supply, provided with a supply circuit, a course over which a dummy may be moved, a dummy, a revolute shaft, electrically controlled means adapted to be actuated by the shaft and to move the dummy over the course, electrically communicating with said supply circuit, a plurality of contacts adapted to be brought in circuit with said electrically controlled means to govern the movement of the dummy actuating means by the shaft, manually operable means controlling the bringing of the various contacts into the supply circuit, and an annunciator adapted to be energized upon the movement of the dummy over the course.

19. The combination with a source of electrical supply, provided with a supply circuit, a course over which a dummy may be moved, a dummy, a revolute shaft, electrically controlled means adapted to be actuated by the shaft and to move the dummy over the course, electrically communicating with said supply circuit, a plurality of contacts adapted to be brought in circuit with said electrically controlled means to govern the movement of the dummy actuating means by the shaft, manually operable means controlling the bringing of the various contacts into the supply circuit, an electrically responsive annunciator, contacts electrically communicating with the annunciator, and means adapted to be actuated by

the dummy to bring the last mentioned contacts into circuit with the source of electrical supply.

20. The combination with a source of electrical supply, provided with a supply circuit, a course over which a dummy may be moved, a dummy, a revolute shaft, electrically controlled means adapted to be actuated by the shaft and to move the dummy over the course, electrically communicating with said supply circuit, a plurality of contacts adapted to be brought in circuit with said electrically controlled means to govern the movement of the dummy actuating means by the shaft, manually operable means controlling the bringing of the various contacts into the supply circuit, an electrically responsive switch, electrically connected with the source of electrical supply, an electro-magnet adapted to actuate the switch to render the manually operable means inoperative upon the dummy actuating means, contacts electrically communicating with the electro-magnet, and means adapted to be actuated by the dummy to bring the last mentioned contacts into such relation with the source of supply so as to actuate the switch.

21. In a device of the class described the combination of a revolute shaft, a drum actuated by the shaft, a course over which a dummy may be moved, a dummy, a reel, a connection between the dummy and the reel whereby the dummy may be displaced over the course, a lug on the reel, a pin mounted reciprocally on the drum adapted to assume positions in and out of driving engagement with the lug on the reel, means normally retaining the pin in driving engagement with the lug, and manually operable means controlling the driving relation of the pin and the lug.

22. In a device of the class described the combination of a revolute shaft, a drum actuated by the shaft, a course over which a dummy may be moved, a dummy, a reel, a connection between the dummy and the reel whereby the dummy may be displaced over the course, a lug on the reel, a pin mounted reciprocally on the drum, yielding means normally retaining the pin in the path of the lug, means to fixedly retain the pin in the path of the lug, and manually operable means controlling the fixation of the last mentioned means.

23. In a device of the class described the combination of a revolute shaft, a drum actuated by the shaft, a course over which a dummy may be moved, a dummy, a reel, a connection between the dummy and the reel whereby the dummy may be displaced over the course, a lug on the reel, a pin mounted reciprocally on the drum, a spring yieldingly retaining the pin in the path of the lug, an armature adapted to fix

the pin in the path of the lug, an electro-magnet operative upon the armature, a source of electrical supply electrically connected with the electro-magnet, electrical contacts adapted to be brought into an electrical circuit embracing the electro-magnet and source of electrical supply, and manually operable means controlling the bringing of the contacts into the said electrical circuit.

24. In a device of the class described the combination of a revoluble shaft, a drum actuated by the shaft, a course over which a dummy may be moved, a dummy, a reel, 15 a connection between the dummy and the reel whereby the dummy may be displaced over the course, a lug on the reel, a pin mounted reciprocally on the drum, a spring 20 yieldingly retaining the pin in the path of the lug, an armature adapted to fix the pin in the path of the lug, an electro-magnet operative upon the armature, a source of electrical supply electrically connected with the electro-magnet, electrical contacts adapted 25 to be brought into an electrical circuit embracing the electro-magnet and source of electrical supply, a manually revoluble shaft, contacts mounted on the shaft adapted to be brought into an electrical circuit 30 embracing the electro-magnet and the source of electrical supply, and a pendulum mounted on the shaft adapted to be actuated by centrifugal force and to determine the bringing of the contacts into such circuit.

35 25. In a device of the class described the combination of a revoluble shaft, a course over which a dummy may be moved, a dummy, electrically responsive means adapted to be actuated by the shaft and to displace 40 the dummy over the course, a source of electrical supply electrically connected with the electrically responsive means, a manually revoluble shaft, contacts mounted on the shaft adapted to be brought into a circuit 45 embracing the electrically responsive means and the source of electrical supply, and a pendulum mounted on the revoluble shaft adapted to be actuated by centrifugal force and to determine the bringing of the contacts into such circuit.

50 26. In a device of the class described the combination of a revoluble shaft, a course over which a dummy may be actuated, a dummy, means adapted to be actuated by the shaft and to move the dummy over the course, electrically responsive means actuated by the shaft adapted to control the transmission of energy from the shaft to the dummy actuating means, manually 55 operable means controlling the electrically responsive means, a source of electrical supply, and a supply circuit into which the electrical responsive means may be brought.

60 27. In a device of the class described the combination with a dummy, a course over

which a dummy may be moved, and means to displace the dummy over the course, of a source of electrical supply, an electro-magnet, an electrically responsive annunciator, and an electrically responsive device 70 adapted to render the dummy displacing device inoperative upon the dummy, wired in parallel and connected with one pole of the source of electrical supply, an electrical contact electrically connected with the 75 other pole of the source of electrical supply, an armature electrically connected with the one contact and adapted to be moved by the dummy into electrical engagement with the other contact and to be then retained in such engagement by the electro-magnet, and an electric switch.

28. In a device of the class described the combination of a dummy, a course over which the dummy may be moved, a revoluble shaft, electrically responsive means adapted to be actuated by the shaft and to control movement of the dummy over the course, a source of electrical supply, a manually revoluble lever, electrical contacts 90 on the lever adapted to be brought into a circuit embracing the source of electrical supply and the electrically responsive means, a pendulum responding to centrifugal force mounted on the lever adapted to control the bringing of the contacts into said circuit, a switch electrically shunted across the contacts, an electrically responsive lock adapted to control the switch, an electric annunciator and an electro-magnet 95 electrically connected in parallel and electrically connected with one pole of the source of electrical supply, and an electrical contact connected with the other pole of the source of electrical supply 100 controlling excitation of the lock, the annunciator and the electro-magnet, to be acted upon by the electro-magnet, and to be actuated by the dummy.

29. In a device of the class described the combination of a dummy, a course over which the dummy may be moved, a revoluble shaft, electrically responsive means adapted to be actuated by the shaft and to control movement of the dummy over the 110 course, a source of electrical supply, a manually revoluble lever, electrical contacts on the lever adapted to be brought into a circuit embracing the source of electrical supply and the electrically responsive means, a pendulum responding to centrifugal force mounted on the lever adapted to control the bringing of the contacts into said circuit, a switch electrically shunted across the contacts, an electrically responsive lock 115 adapted to control the switch, an electric annunciator and an electro-magnet electrically connected in parallel and electrically connected with one pole of the source of electrical supply, an electrical contact con- 120

130

nected with the other pole of the source of electrical supply controlling excitation of the lock, the annunciator and the electro-magnet, to be acted upon by the electro-mag-
5 net, and to be actuated by the dummy, and a switch interposed between the source of electrical supply and the last mentioned contact.

30. A controlling device of the class de-
10 scribed comprising a revoluble shaft, a pen-
dulum pivotally mounted on the shaft, and
electrical contact blocks adapted to be en-
gaged by the pendulum, whereby electrical
circuits passing thru the blocks may be
15 controlled, the pendulum being adapted to
be actuated by centrifugal force resultant
from the rotation of the shaft.

31. In a device of the class described the combination with an electrical circuit of a
20 circuit conditioning device comprising a manu-
ally revoluble shaft, an arm extending from the shaft, contact blocks mounted on the arm, a pendulum in the circuit, pivot-
ally mounted on the arm adapted to be
25 moved on its mounting by the centrifugal force generated by the rotation of the shaft and to be thereby brought into engagement with the blocks.

32. In a device of the class described
30. the combination with a dummy, a course over which a dummy may be moved, and means to displace the dummy over the course, of a source of electrical supply, an electro-magnet, an electrically responsive
35 annunciator, and an electrically responsive device adapted to render the dummy displacing device inoperative upon the dummy, wired in parallel and connected with one pole of the source of electrical supply, an electrical
40 contact electrically connected with the other pole of the source of electrical supply, and an armature electrically connected with one pole of the source of electrical supply and

adapted to be moved by the dummy into electrical engagement with the electrical 45 contact and to be then retained in such engagement by the electro-magnet.

33. In a device of the class described the combination of a series of dummies, courses over which the dummies may be moved, a 50 common means to actuate all the dummies, means normally operating to render the dummy actuating means inoperative on the dummies, and manually operative means adapted to render the second mentioned 55 means inoperative.

34. In a device of the class described the combination of a series of dummies, courses over which the dummies may be moved, a 60 common means to actuate all the dummies, a means individual to each dummy controlling the action of the common means on the dummy associated with such individual means, adapted in its normal condition to render the common means inoperative and 65 in its abnormal condition to permit operation of the common means on the dummy associated with such individual means, and a manually operable means individual to each dummy controlling the individual 70 means.

35. In a device of the class described the combination of a series of dummies, courses over which the dummies may be moved, a 75 common means to actuate all the dummies, a means individual to each dummy controlling the action of the common means on the dummy associated with such individual means, and a manually operable means in-
dividual to each dummy controlling the 80 individual means.

In testimony whereof, I have hereunto
subscribed my name this 20th day of April,
1921.

ROBERT A. ELLISON.
